US00D968591S

(12) **United States Design Patent** (10) **Patent No.:** **US D968,591 S**
(45) **Date of Patent:** **** Nov. 1, 2022**

(54) **SAFETY NEEDLE**

(71) Applicant: **Expressions Design Studio, LLC**,
Union City, NJ (US)

(72) Inventor: **Richard Caizza**, Union City, NJ (US)

(73) Assignee: **Expressions Design Studio, LLC**,
Union City, NJ (US)

(**) Term: **15 Years**

(21) Appl. No.: **29/761,944**

(22) Filed: **Dec. 14, 2020**

(51) LOC (13) Cl. **24-02**

(52) U.S. Cl.

USPC **D24/112**; D24/113; D24/130

(58) **Field of Classification Search**

USPC D24/112-114, 133, 186, 129-130, 127,
D24/108

CPC A61M 5/3216; A61M 5/3129; A61M

(57) **CLAIM**

The ornamental design for a safety needle, as shown and described.

DESCRIPTION

FIG. 1 is a perspective view of a safety needle;

FIG. 2 is a front elevation view thereof;

FIG. 3 is a rear elevation view thereof;

FIG. 4 is a right side elevation view thereof;

FIG. 5 is a left side elevational view thereof;

FIG. 6 is a top plan view thereof; and,

FIG. 7 is a bottom plan view thereof.

The broken lines in the figures illustrate portions of the safety needle which form no part of the claimed design.

1 Claim, 4 Drawing Sheets
